GAME APPARATUS

Claude R. Kirk, Oak Park, and Edward E. Col-
lison, Chicago, Ill., assignors to Standard
Ticket Games Corporation, Chicago, Ill., a cor-
poration of Illinois

Application January 26, 1935, Serial No. 3,542

4 Claims. (Cl. 273—121)

This invention relates to a game apparatus.

This application is a continuation in part of
our copending application, Serial No. 732,776,
filed June 28, 1934, now Patent No. 1,973,815,
5 dated September 18, 1934, on a Game apparatus.

It is an object of this invention to provide
an improved game apparatus which is relatively
simple and inexpensive in construction and effi-
cient in use.

10 Another object of the present application is
to claim, per se, certain features shown and
described in our aforesaid patent.

15 A further object of the present invention is
to provide a device, not shown in our aforesaid
patent, for permitting operation of the coin slide
and associated apparatus if, for any reason,
such, for example, as wear on the parts of the
apparatus which control the score-printing op-
eration and web-severing operation, the opera-
tions of printing the score of the game and
severing the printed ticket from the web or body
20 of the same should take place before the total
number of balls allowed the player for the in-
sertion of a proper coin into the coin aperture
25 of the coin slide has been played, so that, in
this event, the player or proprietor of the game
apparatus with which the present invention is
associated may elevate the remaining balls up
to the level of the playing surface, thereby lock-
30 ing the ball elevating device; and then insert
another coin into the coin aperture of the coin
slide and operate the latter to reset the appa-
ratus back into its initial position ready for
play to be resumed thereon, it being understood
35 that in the apparatus shown in our aforesaid
patent, the coin slide cannot be operated until
the last ball has been played.

Other objects will appear hereinafter.

40 The invention consists in the novel combi-
nation and arrangement of parts to be herein-
after described and claimed.

The invention will best be understood by ref-
erence to the accompanying drawings, showing
the preferred form of construction and in which:

45 Fig. 1 is a fragmentary top plan view of a
game apparatus similar to that shown and de-
scribed in our aforesaid patent;

50 Fig. 2 is a sectional detail view on line 2—2
in Fig. 1, showing in ineffective position, part
of the new device embodied in our present in-
vention and not shown in our aforesaid patent,
for permitting operation of the coin slide and
55 associated apparatus if the score-printing and
web-severing operations should take place be-
fore the last of a predetermined number of balls

allowed the player for the insertion of a coin
into the coin slide has been played;

Fig. 3 is a view similar to Fig. 2 but showing
the parts moving into effective position;

Fig. 4 is a view similar to Figs. 2 and 3 but
5 showing the parts in effective position;

Fig. 5 is a sectional view on line 5—5 in Fig. 3;

Fig. 6 is a sectional view on line 6—6 in Fig. 1;

Fig. 7 is a sectional view on line 7—7 in Fig. 1;

Fig. 8 is a sectional view on the line 8—8 in 10
Fig. 1;

Fig. 9 is a sectional view on line 9—9 in Fig.
1; and

Fig. 10 is a sectional detail view of the score
printing and web-severing device. 15

A game apparatus similar to that shown in
our aforesaid patent is shown in the drawings,
is generally indicated therein at 11, and com-
prises a cabinet 18 within which is arranged a
rotatable score-recording or printing drum 12, 20
a rotatable registering or score-indicating dial
13, and mechanism for operating the said drum
and dial; the cabinet 18 including an inclined
playing board 55 which is provided with ball
25 exit or scoring openings 56 by means of which
the played balls are conducted into inclined
runways 57 which are arranged below the in-
clined playing board 55.

Arranged within a housing 14 in the cabinet
11 is a rotary ball elevating disc 15, the disc 15 30
being operated by means 16, etc., (shown in our
aforesaid patent) and including the hand lever
17 which projects exteriorly of the cabinet 18
for operation by the player.

Carried by the rotary elevator disc 15 on the 35
inner lateral side thereof (left side, Fig. 5) are
a cam 19 and a laterally projecting arm or stop
member 20 (Fig. 5).

Mounted on a horizontal shaft 21 which ex-
tends transversely across the cabinet 18 below 40
the playing surface of the latter is a latch or
stop arm 22 which has an angled or laterally
extending end portion 23 (Fig. 5) which is
adapted to ride the surface of the cam 19 as
the rotary elevator disc 15 is operated. This 45
angled end portion 23 of the stop member 22
projects through an opening 74 which is formed
in the wall of the elevator housing 14 (Figs. 2,
3 and 4) and when the rotary elevator disc 15
comes into position to elevate the last of a pre- 50
determined number of balls allowed the player
for a proper coin inserted into the coin aper-
ture of the coin slide 24, the angled end portion
23 of the latch arm 22 engages the edge or
55 surface 73 of a laterally projecting latch arm or

lug 29 which is carried by the disc 15 and thereby locks the elevator disc 15 against further operation or rotation (clockwise, Figs. 2, 3 and 4).

- 5 It is desirable to permit operation of the coin slide 24 and associated apparatus if, for any reason, the score-printing and web-severing operations, explained more fully in our aforesaid patent, should take place prior to the time that 10 the last of the predetermined number of balls allowed the player has been played. This may occur from, or caused by, wear on those parts of the apparatus, such as the ratchets 53 and 62, which control the score-printing and web-severing 15 operations.

To this end we mount on the inner wall of the elevator housing 14 a latch member 25, which is pivotally mounted at its lower end on the elevator housing as at 27, and this latch member 20 25 carries a laterally projecting pin 26 (Fig. 5) which works in an opening 29 that is formed in a wall of the elevator housing 14; this pin 26 being adapted to ride the cam 19 carried by the elevator disc 15.

- 25 The latch member 25 is pivoted (counterclockwise, Figs. 2, 3 and 4) by the action of gravity and the extent of its movement is limited by the engagement of its laterally extending pin 26 with the walls of the opening 29.
- 30 The coin slide 24 has a pin and slot connection 31 (Fig. 9) with a slide bar 32 and the latter is, in turn, pivotally connected, as at 34, to the upper end portion of a link 33, the latter being mounted at its lower end upon a horizontal shaft 35 which is arranged in the cabinet 18.

- 40 Mounted on the shaft 21 which carries the stop member 22 (Figs. 2, 3, 4, 7 and 9) is a coin slide latch member 36 which is provided with an elongated slot 37, the latter having a notch 38 at one end thereof, and carried by the link 33 and movable in the slot 37 is a laterally projecting pin 39.

- 45 When the stop member 22 and its supporting shaft 21 are disposed in the position of Fig. 2 and the coin slide 24 is in coin-receiving position, the pin 39 is disposed in the notch 38 of the latch member 36 and the latter is disposed in horizontal position (as in dotted lines, Fig. 9), and when so disposed the engagement of the pin 50 39 in the notch 38 prevents inward movement (right to left, Fig. 9) of the coin slide 24, and in this position of the parts the stop member 22 is disposed as in Figs. 2 and 3.

- 55 Carried by the shaft 21 and depending therefrom (Fig. 7) is an arm 40 and engageable with the lower end portion of this arm 40 is a cam 41 which is arranged on a horizontal shaft 42 which is arranged in the cabinet 18. Mounted on this shaft 42 is a disc 43 to which is eccentrically connected, as at 44 (Fig. 9), one end portion of an arm 45, the other end portion of the arm 45 being connected to a pin 46 which works in a slot 48, the slot 48 being formed in a vertical supporting wall 49 which is arranged in the cabinet 18; this pin 46 being carried by a pivoted pressure or impression-transmitting member 47 by means of which the imprint-receiving web 50 is forced into printing engagement with the printing drum 12, as more fully set forth in our aforementioned patent; the pressure member 47 also functioning to sever the printed portion of the web 50 from the body of the same, approximately at the same time (or slightly before or after, as may be desired) that the 70 score-printing operation takes place, whereupon

the printed and severed portion of the web falls onto an inclined chute 52 (Figs. 8 and 10) and is dispensed to the player by way of a dispensing outlet formed in the cabinet 18 (not shown).

5 As the played balls travel down the runways 57 (Fig. 6) they pass into a chute 58 from which they fall onto an arm 59 of an escapement dog 60, the dog 60 having an arm 64 which engages with the teeth of a ratchet 53 which is arranged upon a horizontal shaft 63 (Figs. 6 and 9); the dog 60 also having an escapement arm 64 which engages with the teeth of a ratchet 62 which is also arranged upon the shaft 63 adjacent the ratchet 53 but is somewhat smaller in diameter than the latter.

10 Arranged upon the shaft 63 is a tensioned operating spring 65 (Fig. 1) and an arm 66, the arm 66 being engageable with one end portion of a pivotal latch member 67 and the latter having an arm 69 which is engageable in a notch 68 formed in the periphery of the disc 43 (Fig. 9).

15 After the ratchets 53 and 62 have been advanced a predetermined circumferential distance by operation of the spent playing balls 10 upon the dog 59—60—51—64, the arm 64 of the dog 60 engages an uninterrupted or smooth surface 71 which is formed on the periphery of the ratchet 53 (Fig. 6), whereupon the spring 65 rotates the shaft 63 (clockwise, Figs. 30 6 and 9). This movement of the shaft 63 causes the arm 66 thereon to engage the dog 67, thereby pivoting the end portion 69 of the latter out of latching engagement with the notch 68 in the disc 43.

20 Thereupon the shaft 42 and the disc 43 are rotated (clockwise, Fig. 9, counterclockwise, Fig. 7) by the action of a spring 54 which is arranged upon the shaft 42. This action of the shaft 42 causes the cam 41 carried thereby 25 to engage the lower end portion of the arm 40, thereby rocking the shaft 21 (clockwise, Fig. 7), and in this manner pivoting the slotted latch member 36 from dotted to full line position, Fig. 7, thus freeing the pin 39 from engagement 45 in the notch 38 and thereby freeing the coin slide 24 and associated parts for operation. At the same time, this movement of the shaft 21 (clockwise, Fig. 7, counterclockwise, Figs. 2, 3 and 4) pivots the stop member 22 (counterclockwise, Figs. 2, 3 and 4) into the dotted line 50 position of Fig. 3.

25 The latch member 25 then pivots by gravity (counterclockwise, Figs. 2, 3 and 4) into the position of Fig. 4 wherein it is held by engagement of the angled end portion 28 of the latch member 25 under the angled end portion 23 of the stop member 22, the said stop member 22 being thus retained in the position of Fig. 4, thereby preventing the stop member 22 and its supporting shaft 21 from returning to the position of Fig. 2, thereby retaining the slotted latch member 36 in raised position, as in dotted lines, Fig. 7, and thus permitting operation of the coin slide 24 and associated parts, it being noted that the coin slide and associated parts could not be operated if the stop member 22 and shaft 21 were allowed to pivot from their position of Fig. 4 into the position shown in Figs. 2 and 3, immediately after the score-printing and web-severing operations, since in the latter position of the shaft 21 the slotted latch member 36 is disposed in horizontal position, as in dotted lines, Fig. 7, and in this position of the parts the pin 39 is disposed in the 75

notch 38, so that the coin slide 24 and associated parts could not be operated if the web-printing and severing operations were to take place prior to the time the last of a predetermined number 5 of balls allowed the player for each coin inserted into the coin slide 24 is played.

As the coin slide 24 and slide bar 32 are returned (by means of a spring, not shown) into coin-receiving position (left to right, Fig. 9) the 10 pin 39 travels back into the notch portion 38 of the slot 37 in the latch member 36 (left to right, Fig. 9), and in this position prevents further operation of the coin slide 24 and associated parts until the last of the predetermined 15 number of balls allowed the player is played. During this operation of retracting the coin slide 24 the shaft 21 and the stop member 22 are again rotated (clockwise, Figs. 2, 3 and 4) into the position of Fig. 4, and as the player continues 20 to operate the rotary elevator disc 15, and thereby elevate the remaining balls up to the level of the playing surface 55, the cam 19 on the rotary elevator disc 15 eventually engages under the pin 26 carried by the latch member 25 and in so doing pivots the latter member 25 (clockwise, Figs. 2, 3 and 4) from the position of Fig. 4 into its initial position of Figs. 2 and 3.

The stop member then pivots by gravity into its full line position (Fig. 6) and in so doing, 30 the angled end portion 23 of the stop member 22 engages in an offset or notched portion 72 of the latching lug 20 (Figs. 4 and 6). In this position of the parts the engagement of the arm 23 of the stop member 22 in the notched or 35 offset portion 72 of the lug 20 prevents further operation of the rotary elevator disc 15 (clockwise, Figs. 2, 3 and 4) but at the same time retains the latch member 36 in full line position of Fig. 7 so that the coin slide 24 may be operated, whereupon the stop member 22 is again 40 pivoted (counterclockwise, Figs. 2, 3 and 4) and in so doing, rides out of the notched portion 72 of the lug 20 into position to engage the portion 73 of the same when the elevator disc 15 has 45 made another revolution and the last ball has been played.

The possibility that the score-printing and web-severing operations may take place prior to the time the last ball has been played are materially reduced by the provision, in the present invention, of the double ratchet 62—53 and by reason of the additional fact that each of the arms 61 and 64 of the pawl or dog 60 engages only one of the ratchets whereas in our aforementioned patent, both arms 61 and 64 of the dog or pawl 60 engaged a single ratchet and had a tendency to wear out the teeth of the same and thereby increase the possibilities that the score-printing and web-severing operations 50 might take place prior to the time the last of the predetermined number of balls has been played. This likelihood is materially decreased by the provision of the double ratchet 53—62, 55 operating as hereinbefore set forth.

While we have illustrated and described the preferred form of construction for carrying our invention into effect, this is capable of variation and modification, without departing from the 60 spirit of the invention. We, therefore, do not wish to be limited to the precise details of construction set forth, but desire to avail ourselves of such variations and modifications as come within the scope of the appended claims.

Having thus described our invention, what we

claim as new and desire to protect by Letters Patent is:

1. In a game apparatus, the combination of: a cabinet including a member providing a playing surface having ball exit or scoring openings therein; a score recording or printing drum in the cabinet; means for elevating balls one at a time from a point below the playing surface up to the level of the same; an inscription-receiving web in the cabinet; means automatically urging the said web into printing engagement with the said printing drum after a predetermined number of balls have been elevated by said elevating means from a point below the said playing surface up to the level of the same; a 15 member slidably mounted in a wall of said cabinet; means normally latching the said slidable member against operation until the score-printing operation takes place; and means for releasing the said latching means from latching engagement with the said slidable member when the score-printing operation takes place.

2. In a game apparatus, the combination of: a cabinet including a member providing a playing surface having ball exit or scoring openings therein; a score recording or printing drum in the cabinet; means for elevating balls one at a time from a point below the playing surface up to the level of the same; an inscription-receiving web in the cabinet; means for severing the 30 printed portion of the web from the body of the same approximately at the time the score-printing operation takes place; means automatically urging the said web into printing engagement with the said printing drum after a predetermined number of balls have been elevated by said elevating means from a point below the said playing surface up to the level of the same; an operating member movably mounted upon a wall of said cabinet; means normally latching the 35 said operating member against operation until the web-severing operation takes place; and means for releasing the said latching means from latching engagement with said operating member when the web-severing operation takes 40 place.

3. In a game apparatus, the combination of: a cabinet including a member providing a playing surface having ball exit or scoring openings therein; a score recording or printing drum 50 in the cabinet; means for elevating balls one at a time from a point below the playing surface up to the level of the same; an inscription-receiving web in the cabinet; means for severing the printed portion of the web from the body 55 of the same approximately at the time the score-printing and web-severing operations take place; a member slidably mounted in a wall of said cabinet; means normally latching the said slid- 60 able member against operation until the score-printing and web-severing operations take place; and means for releasing the said latching means from latching engagement with said slid- 65 able member when the web-severing and score-printing operations take place.

4. In a game apparatus, the combination of: a cabinet including a member providing a playing surface having ball exit or scoring openings therein; a score recording or printing drum 70 in the cabinet; means for elevating balls one at a time from a point below the playing surface up to the level of the same; an inscription-receiving web in the cabinet; means automatically urging the said web into printing engagement 75

with the said printing drum after a predetermined number of balls have been elevated by said elevating means from a point below the said playing surface up to the level of the same; 5 means for severing the printed portion of the web from the body of the same after the score-printing and web-severing operations take place; a member slidably mounted in a wall of said cabinet; means normally latching the said slid-

able member against operation until the score-printing and web-severing operation takes place; and means for releasing the said latching means from the latching engagement with said slidable member after the score-printing and web-severing operations take place. 5

CLAUDE R. KIRK.
EDWARD E. COLLISON.
